CLAIM

The ornamental design for a mobile vending trailer, as shown and described.

DESCRIPTION

FIG. 1 is a first perspective view of a mobile vending trailer, illustrating the new, original, and ornamental design;

FIG. 2 is a second perspective view of a mobile vending trailer, illustrating the new, original, and ornamental design;

FIG. 3 is a first side view of a mobile vending trailer, illustrating the new, original, and ornamental design;

FIG. 4 is a second side view of a mobile vending trailer, illustrating the new, original, and ornamental design;

FIG. 5 is a top view of a mobile vending trailer, illustrating the new, original, and ornamental design;

FIG. 6 is a bottom view of a mobile vending trailer, illustrating the new, original, and ornamental design;

FIG. 7 is a first end view of a mobile vending trailer, illustrating the new, original, and ornamental design; and,

FIG. 8 is a second end view of a mobile vending trailer, illustrating the new, original, and ornamental design.

In the drawings, the broken lines depict portions of the design that form no part of the claim.
